P. KARSACK

COVER FOR BOILERS

Filed March 23, 1922

FIG. 1.

FIG. 3.

FIG. 4.

FIG. 5.

FIG. 2.

Inventor

P. Karsack

J. N. Bryant.

Attorney

UNITED STATES PATENT OFFICE.

PAUL KARSACK, OF CLEVELAND, OHIO.

COVER FOR BOILERS.

Application filed March 23, 1922. Serial No. 546,094.

To all whom it may concern:

Be it known that I, PAUL KARSACK, a citizen of Hungary, residing at Cleveland, in the county of Cuyahoga and State of Ohio, have invented certain new and useful Improvements in Covers for Boilers, of which the following is a specification.

This invention relates to certain new and useful improvements in coverings for boilers and has particular reference to the idea of clamping or locking the cover to the boiler.

The primary object of the invention resides in the provision of a locking device carried by the outer side wall of the boiler adapted to be moved into engagement with a cover placed upon the boiler to lock the cover in position thereon, the cover being provided with a shiftable plate section adapted to be positioned in line with an opening in the cover with the plate section having a plurality of perforations to permit the fluid contents of the boiler being drained therefrom without the necessity of removing the cover, and also permits the contents of the boiler being removed through the opening in the cover by shifting the perforated plate laterally of said cover opening.

With the above general objects in view the invention consists of the novel combination and arrangement of parts hereinafter more fully described in connection with the accompanying drawing, and in which like reference characters designate corresponding parts throughout the several views.

In the drawings:

Fig. 1 is a vertical sectional view of a boiler constructed in accordance with the present invention, showing the tensioned clamping arm carried by the boiler for engagement with the cover,

Fig. 2 is a top plan view of the boiler and cover showing the shiftable perforated plate section carried by the cover and registering with the opening in the cover,

Fig. 3 is a side elevational view of the boiler showing the clamping device engaging the cover,

Fig. 4 is a detailed sectional view taken on line IV—IV of Fig. 3, and drawn to an enlarged scale, showing the tensioned clamping arm and the lock therefor to retain the same in engagement with the boiler cover, and

Fig. 5 is a detailed sectional view similar to Fig. 4, showing the clamping devices disengaged from the cover.

Referring more in detail to the accompanying drawings there is illustrated a boiler embodying the side wall 1 upon which a cover 2 is mounted with a depending annular flange 3 carried by the cover enclosing the upper end of the side wall 1 of the boiler. An inwardly directed flange 4 adjacent the point of connection between the top wall of the cover and the side flange 3 extends inwardly of said boiler walls to rest upon the upper edge thereof as shown in Figs. 4 and 5 to properly support the cover in position on the boiler.

The top wall 2 of the cover is provided with a segment shaped opening 5 as shown in Fig. 2, while a perforated segment-shaped plate 6 pivotally supported upon the handle 7 of the cover is adapted to be shifted to a position registering with said opening 5 as shown in Fig. 2 to provide a strainer plate section in the cover for purposes of draining the boiler without the necessity of removing the cover. It is also to be understood that the plate section 6 may be shifted to the position laterally of the opening 5 to permit the contents of the boiler being entirely removed.

The locking connection between the boiler and the cover is shown more clearly in Figs. 1, 4, and 5, the side flange 3 of the cover carrying adjacent the lower end thereof diametrically opposite lugs 8 provided with a recess 9. A spring strip 10 is secured as at 11 to the side wall 1 of the boiler and carries upon its upper end thereof an arm 12 provided with an inwardly directed angle lug 13 upon the upper end thereof, that registers with the recess 9 of the cover lug 8. When the cover 2 is placed upon the boiler, the spring arm 10 normally holds the arm 12 positioned outwardly of the side flange 3 of the cover so that the cover may be easily mounted upon the boiler with the inwardly directed flange 4 resting upon the upper edge thereof.

With the cover 2 in position, a strap 14 of U-shaped formation hinged as at 15 to the side wall of the boiler, encloses the spring strip 10 so that when the strap 14 is moved outwardly from the position shown in Fig. 5, to that shown in Fig. 4, the U-shaped strap 14 engages the spring strip 10 to force the same into position.

wardly towards the side of the boiler and to correspondingly move the arm 12 towards said boiler to position the lug 13 upon the arm in the lug recess 9, the cover being securely retained in position upon the boiler by the locking arm 12.

From the above detailed description of the device it is believed that the construction and operation thereof will at once be apparent, and while there is herein shown and described the preferred embodiments thereof, it is to be understood that various changes are contemplated that will fall within the scope of the subject matter claimed.

I claim:

In a device of the class described, a boiler, a cover therefor, a depending side flange carried by the cover and closing the upper end of the boiler, diametrically opposite lugs

carried by said flange with a socket formed in the outer face of each lug, a spring strip secured at one end to the side wall of the boiler, a rigid locking arm fixed to the other end of the spring strip and carrying an angle lug at the upper end adapted to be received in the lug recess to retain the cover in position on the boiler, and a U-shaped strap hinged to the boiler enclosing the spring strip and adapted to be moved into engagement with said spring strip to cause the lug carried by the locking arm to be received in the recess formed in the cover flange lug.

In testimony whereof I affix my signature.

PAUL KARSACK.
